UNITED STATES PATENT OFFICE.

JOSEPH H. COLEMAN, OF TOTTENHAM, ONTARIO, CANADA.

FARE-COLLECTOR.

No. 827,451.

Specification of Letters Patent.

Patented July 6, 1909.

Original application filed June 4, 1908, Serial No. 436,701. Divided and this application filed July 26, 1908.
Serial No. 446,877.

To all whom it may concern:

Be it known that I, Joseph H. COLEMAN, of the town of Tottenham, in the Province of Ontario, Canada, have invented certain new and useful Improvements in Fare-Collectors, of which the following is a specification.

This application is a division of my U. S. application No. 436,701, filed June 4th, 1908, 10 and relates to the fare receptacle or hopper disclosed therein but not claimed. In devising such apparatus several requirements must be kept in view. First, it must be so constructed as to make it impossible for the 15 passenger to pass off a worthless or imitation fare undetected; second, it must be so constructed as to make it impossible for the passenger to deposit his fare in the apparatus in such a way that the conductor can 20 remove it and appropriate it; third, the abstraction of individual fares after they have passed into the apparatus must be prevented. I achieve these objects by the constructions I will now describe.

25 Figure 1 is a perspective view of the top of a fare collecting device provided with my improved receptacle. Fig. 2 is a side elevation of the same partly in section. Fig. 3 is an end view of the same with the casing 30 partly broken away. Fig. 4 is a plan view of the rocking bottom of the fare receptacle in its normal position. Fig. 5 is a similar view showing the bottom rocked to "turn 35 down" a fare. Fig. 6 is an end elevation showing the rocking bottom and the swinging gate which normally closes the opening through which the fares are "turned down." Fig. 7 is a side elevation showing the arm 40 which limits the movements of the rocking bottom. Fig. 8 is a cross section of one of the sides of the hopper of the fare receptacle. Fig. 9 is an enlarged top plan view of one corner of the hopper rim showing one of the 45 outwardly extending projections formed at the junctions of the edges of said rim.

In the drawings like figures of reference indicate corresponding parts in the different figures.

The device is intended for use as described in my prior patent No. 875,781 and is located beside the entry to the car. The parts are all contained within the casing 1, of suitable shape and having its top formed as a table or counter on which the conductor 50 may mark his transfers, make change and

conduct his other business with the passengers entering the car. At the top of the casing is located a fare collecting receptacle 2. This fare receptacle comprises four glass walls 3, suitably held in a metal frame. The bottom of the receptacle is closed by a rocking bottom 4, intended to retain the fares until the latter are properly "turned down" by the conductor. This rocking bottom comprises a segment of a cylinder closely 55 fitted to the bottom of the frame of the receptacle 2. A flat is formed at one part of the surface of this segment which normally forms a flat bottom for the receptacle as shown in Fig. 2. The curved outer surfaces 60 of the rocking bottom are provided with circumferential ribs 5. The bottom of the outer wall of the receptacle formed by part of the frame supporting the glass plates is 65 suitably notched to fit these ribs. (See 70 particularly Figs. 2, 4 and 5.) The purpose 75 of this construction is to prevent tickets or cash fares becoming jammed between the surface of the rocking bottom and the outer wall of the receptacle. An opening 6 is 80 formed between the bottom of the opposite wall of the fare receptacle and the rocking bottom and through this opening the fares 85 are "turned down"; when the bottom is 90 rotated to the position shown in Fig. 5. ab This opening is normally closed by the swinging gate 7 suitably hinged at its upper edge (see particularly Figs. 2 and 6.) The 95 opening 6 prevents any jamming of fares when a number are "turned down" together 100 and at the same time the gate prevents any individual fares from falling through until regularly "turned down" by the conductor.

The lower edge of the gate is preferably 105 notched to fit the ribs 5 of the rocking bottom. The rocking bottom is operated by means of a hand lever 8 suitably pivoted on the frame of the apparatus and extending to a point convenient to the conductor's hand. To its lower end is pivotally connected the 110 link 9, the other end of which is connected to the arm 10 connected to the rock shaft 11 to which the rocking bottom is secured. This shaft is journaled in suitable brackets 12, formed on or secured to the frame of 115 the machine (see Figs. 2, 3, 6 and 7). To limit the movement of the rocking bottom in either direction it is secured to the shaft 11 an arm 11 and secured to the frame at either side thereof the stops 12 with which the end 120

of the arm may engage. I also secure to the lever 8 a coil spring 38, the other end of which is secured to the frame. This spring tends to retain the parts in their normal position.

For the purpose of preventing the illicit abstraction of fares from the fare receptacle, I have adopted the construction I will now describe.

10. A hopper is formed at the upper part of the fare receptacle by means of the transparent plates 43, which have an opening between their lower ends preferably directed to one side as shown in Fig. 2. Below the upper plates are secured the oppositely inclined baffle plates 44 which are also transparent. The opening between the lower ends of these plates is preferably out of alignment with the opening between the lower ends of the hopper plates and to the opposite side of the center of the plane to that toward which the opening between the lower ends of the upper plates faces. The purpose of this is two-fold. It is thereby rendered impossible to introduce any tool through to the bottom of the receptacle to abstract coins and any fares are directed toward the outer side of the rocking bottom where they are readily seen by the conductor and in such a position that if the conductor happens to have partly turned the rocking bottom to "turn down" a fare, the last introduced fare will not slide through the opening 6 without being seen but will fall onto the 25 ribbed portion of the bottom which now begins to appear at the bottom of the receptacle.

Much difficulty was experienced with the fare receptacle as it was constructed. The 40 walls of the hopper at the upper part of the receptacle being of plain glass, coins were wetted and would then stick to the walls of the hopper when pressed on and were subsequently appropriated by the conductor. 45 Much difficulty was experienced in overcoming this trouble, but it was finally accomplished by the following construction:—Instead of forming the side walls of the hopper with continuous plane surfaces, they were 50 formed with discontinuous surfaces, preferably by forming them with a series of downwardly directed ribs 45. (See particularly Figs. 1, 2 and 8.) This ribbing by preventing any large or continuous plane of 55 contact between the coin and the walls of the hopper effectively overcame this method of illegally appropriating fares. I do not desire to limit myself, of course, to the specified method of forming the discontinuous 60 surfaces shown in the drawings as many variations may be devised which would fall within the scope of my invention.

Further trouble was experienced through parties desirous of cheating the apparatus 65 for the benefit of the conductor depositing

wetted coins on the edges of the rim of the hopper or on the angle where the two sides meet. It was found necessary therefore to bevel the edges of the rim 33 of the hopper almost to a knife edge so that no coin 70 could be balanced thereon as a passenger passed the apparatus. Even though the edges were beveled to a knife edge, it was still possible to rest a coin on the angles between them and I have therefore provided 75 each angle with an upward projection 54 beveled or tapered to a rounded point on which no coin can rest. The combination of these two features, the beveled edges of the rim and the upward projections at the corners, has resulted in a complete defeat of such attempts to beat the apparatus.

What I claim as my invention is:—

1. In fare collecting apparatus a fare hopper having ribbed sides.
2. In fare collecting apparatus a fare hopper having transparent ribbed sides.
3. In fare collecting apparatus a fare hopper having the surfaces down which the fares move formed of a series of downwardly directed ribs.
4. In fare collecting apparatus a wide-mouthed fare hopper having discontinuous imperforate inside surfaces.
5. In fare collecting apparatus a wide-mouthed fare hopper having transparent sides with discontinuous imperforate inside surfaces.
6. In fare collecting apparatus a fare receptacle comprising four transparent walls, two transparent inclined plates forming with the upper part of the receptacle a fare hopper; and two inclined baffle plates below the hopper plates having an opening between their adjacent ends out of alignment with the discharge opening of the hopper.
7. In fare collecting apparatus a fare receptacle comprising four transparent walls, two transparent inclined plates forming with the upper part of the receptacle a fare hopper; and two transparent inclined baffle plates below the hopper plates having an opening between their adjacent ends out of alignment with the discharge opening of the hopper.
8. In fare collecting apparatus a fare receptacle comprising four transparent walls, two transparent inclined plates having discontinuous upper surfaces forming with the upper part of the receptacle a fare hopper; and two inclined baffle plates below the hopper plates having an opening between their adjacent ends out of alignment with the discharge opening of the hopper.
9. In fare collecting apparatus a fare receptacle in combination with a rocking bottom, therefore having its external surface struck on a curve with the same center as that on which the bottom rocks and formed with external circumferentially arranged

ribs, one of the walls of the receptacle at its lower end being notched to receive the ribs.

10. In fare collecting apparatus a fare receptacle in combination with a rocking bottom therefor having its external surface struck on a curve with the same center as that on which the bottom rocks and formed with external circumferentially arranged ribs, one of the walls of the receptacle at its lower end being notched to receive the ribs and the opposite wall at its lower end being cut away to leave a space for the discharge of fares.

11. In fare collecting apparatus a fare receptacle in combination with a rocking bottom therefor having its external surface struck on a curve with the same center as that on which the bottom rocks and formed with a flat at one part of its surface, the remainder being formed with circumferentially arranged ribs, one of the walls of the receptacle at its lower end being notched to receive the ribs.

12. In fare collecting apparatus a fare receptacle in combination with a rocking bottom therefor having its external surface struck on a curve with the same center as that on which the bottom rocks and formed with a flat at one part of its surface, the remainder being formed with circumferentially arranged ribs, one of the walls of the receptacle at its lower end being notched to receive the ribs and the opposite wall at its lower end being cut away to leave a space for the discharge of the fares.

13. In fare collecting apparatus a fare receptacle in combination with a rocking bottom therefor having its external surface struck on a curve with the same center as that on which the bottom rocks and formed with external circumferentially arranged ribs, one of the walls of the receptacle at its lower end being notched to receive the ribs and the opposite wall at its lower end being cut away to leave a space for the discharge of fares; and a hanging gate pivoted in said opening.

14. In fare collecting apparatus a fare receptacle in combination with a rocking bot-

tom therefor having its external surface struck on a curve with the same center as that on which the bottom rocks and formed with external circumferentially arranged ribs, one of the walls of the receptacle at its lower end being notched to receive the ribs and the opposite wall at its lower end being cut away to leave a space for the discharge of fares; and a hanging gate pivoted in said opening and notched to receive the ribs.

15. In fare collecting apparatus a fare receptacle in combination with a rocking bottom therefor having its external surface struck on a curve with the same center as that on which the bottom rocks and formed with a flat at one part of its surface, one of the walls of the receptacle parallel to the axis of the bottom being cut away at its lower end to leave a space for the discharge of fares; and a hanging gate pivoted in said opening.

16. A fare hopper having the rim of its mouth formed of a plurality of sides meeting at an angle to one another to form the corners of the hopper, the top surfaces of said sides forming the rim of the hopper and being beveled upwardly substantially to an edge, and having outwardly extending projections formed at the junctions of the beveled edges of the hopper rim to prevent fares being balanced on the rim at the points of such junctions.

17. A fare receptacle having a partly flattened curved rocking bottom with its external curved surfaces struck on a curve with the same center as that on which the bottom rocks in combination with a hopper formed above the bottom with its discharge opening adapted to direct fares toward the side of the bottom from which the said bottom moves in rocking.

Dated at Toronto, in the Province of Ontario, Canada, this 17th day of July 1908.

JOSEPH H. COLEMAN.

In the presence of—

JOHN G. RIDOUT,
F. W. MCKENDRICK.
